SAFETY ATTACHMENT FOR PUNCH PRESSES

Casper C. Goldbeck, Camden, N. J.

Application June 26, 1940, Serial No. 342,570

5 Claims. (Cl. 192—127)

This invention relates to punching machines or presses and more particularly to a safety attachment by means of which the operation of the punch or press may be stopped when the dies become clogged with material.

At the present time in the operation of punches or presses for forming ends of cans, considerable difficulty is experienced in the accumulation of punched out material which sticks in the movable die and causes considerable damage not only to the dies but to the press or machine proper. Various safety devices have been applied to the punches or presses by means of which the operating lever may be shifted to stop the machine and while attempts have heretofore been made to provide a safety means to stop the machine when punched out ends accumulate in the dies, such safety means have been of such a delicate nature that the vibration of the punch or press has a tendency to render the safety devices ineffective. It is, therefore, an object of this invention to provide a safety means of an automatic character which is operatively connected to the starting and stopping lever of the machine through the solenoid lever operator at present forming part of the machine and which is so constructed as to immediately stop the operation of the machine after not more than two ends are accumulated in the dies.

Another object of this invention is to provide a safety attachment of this kind which is connected to the flexible end engaging member which is mounted on the movable die and which flexible member is adapted to strike the ends as they are released from the dies so as to force the ends to lie flat on the chute leading from the dies, the chute having a means associated with the flexible end engaging member for closing a circuit to the solenoid lever operator when an end is not discharged from the dies.

A further object of this invention is to provide a safety means of this kind which is simple in construction and may be mounted on the present parts of a punch or press and which is not readily affected by vibrations of the press or punch but which will be positive in its operation so that the dies and the press or punch apparatus will not be damaged by accumulation of ends in one or the other of the dies as is at present the case.

To the foregoing objects and to others which may hereinafter appear, the invention consists of the novel construction, combination and arrangement of parts as will be more specifically referred to and illustrated in the accompanying drawing, wherein is shown an embodiment of

the invention, but it is to be understood that changes, modifications and variations may be resorted to which fall within the scope of the invention as claimed.

5 In the drawing—

Figure 1 is a fragmentary side elevation partly in section and partly diagrammatic of the dies of a can end, punch or press apparatus having a safety attachment constructed according to this invention connected therewith.

Figure 2 is a plan view of the stationary die and the discharge chute showing the manner of mounting a portion of the safety attachment in the chute.

Figure 3 is a bottom plan of the flexible end engaging member removed from the press and having a portion of the safety attachment mounted thereon; and

Figure 4 is a fragmentary view in inverted plan of the stripper with the flexible flapper attached thereto.

Referring to the drawing, the numeral 10 designates generally a plunger or die head which has mounted thereon a movable die member 11. The die member 11 on its under face is formed with an annular outer cutting edge 12 and an annular end forming channel 13. The under or lower face of the die member 11 may also be formed with additional grooves 14 depending only upon the shape of the end which it is desired to form by the die structure. A substantially stationary or lower die 15 is disposed in confronting relation to the movable die member 11 and is formed with complementary ribs and grooves 16 and 17 which are adapted to confront the grooves 13 and 14 and any additional grooves or projections which are formed in the upper or movable die member 11. An annular cutter 18 is disposed below the movable die 11 and is positioned about the lower die member 15. The cutter 18 is stationary and is secured to the lower portion 19 of the press. A strip positioning or holding ring 20 is interposed between the cutter 18 and the lower die member 15 and is adapted to engage the under surface of the strip 21 out of which the can ends are to be punched.

A cylindrical or annular end stripper 22 is slidably disposed about the movable die member 11, being provided at its upper edge with an annular flange 23 formed with openings 24. A plurality of stripper guide rods or bolts 25 are secured to the head 10 and loosely engage through the openings 24 in the flange 23. A spring 26 is positioned about each bolt or guide rod 25 and at one end bears against the under-

side of head 10 and at the other end engages against the upper face of the flange 23 so as to constantly urge the stripper 24 to a stripping or operative position with the lower edge of the stripper 22 below the lower cutting edge 12 of the die 11.

The structure hereinbefore described is conventional in presses or punches and is here disclosed as one type of punch or press with which the hereinafter described safety attachment may be combined. A chute 27 is disposed on the rear side of the press being positioned with the upper edge thereof adjacent the cutter 18 and the chute 27 as shown in Figure 1 is disposed in a downwardly and rearwardly inclined position so as guide the punched material into a suitable receptacle or other conveying means. The chute 27 comprises an inclined bottom wall 28 and up-standing side flanges 29. At the present time when the ends punched out by the two dies 11 and 15 fall onto the upper surface of the chute 27, these ends are forced to assume a flat position with respect to the chute 27 by means of a flexible member 30. This flexible member 30 is formed of leather or other suitable flexible material and one end of the flapper or end engaging member 30 is fixed relative to the flange 23 of the stripper 22 as shown in Figure 4 so that the flapper 30 will be disposed in a position overlying the chute 27 and in a position extending lengthwise of the chute 27.

At the present time the press or punch structure is started and stopped by means of an operating lever 31 which is positioned at one side of the machine and also associated with the operating lever 31 is a solenoid structure 32. This solenoid structure 32 is at present connected to various portions of the press or punch so as to shift the lever 31 to a stopping position in the event undesirable conditions exist in the several parts of the machine. The solenoid 31 is connected to a suitable source of electric current supply and is normally inactive, being rendered active upon operation of one or more of the several safety devices connected therewith.

In order to provide a means whereby the solenoid 32 may be rendered active when the die member 11 is operating and when one or more of the ends cut from the supply strip 21 stick in the recesses of the die 11, I have provided a switch structure including a flexible metal strip 33. This strip 33 is formed with a downwardly arched or arcuate portion 34 and a straight portion 35 which is secured as by a bolt 36 to the under side of the flapper or flexible member 30. The opposite end 37 of the switch member 33 is free and slidably engages the under face of the flexible member 30 adjacent the free end thereof. The bolt 36 not only constitutes a means for holding the flexible member 33 on the flexible strip 30 but also constitutes a terminal by means of which a conductor 38 may be connected to the switch member 33. The conductor 38 may be connected to a portion of the press or machine to form a ground which ground is connected as shown diagrammatically in Figure 1 to one side of the solenoid 32.

The bottom 28 of the chute 27 is formed with a slot 39 which is so positioned that when the flexible member 30 is flexed downwardly as shown in dotted lines in Figure 1, the arched switch member 33 will project through the slot 39. A contact member 40 is secured in any suitable manner to the underside of the chute 27 and is disposed substantially centrally of the slot 39. 75

This contact member 40 is connected by means of a conductor 41 to the electric current supply source which is connected to the solenoid 32 so that when the switch member 33 engages at contact 40 a circuit will be completed to the solenoid 32. As shown in Figure 1, the contact member 40 is positioned slightly below the upper surface of the bottom wall 28 of the chute 27 so that when an end lies flat on the upper surface 10 of the bottom wall 28 and the flexible member 30 is flexed downwardly, the electric circuit to the solenoid 32 will not be completed through the end engaging over the slot 39.

However, in the event one or more of the can ends should stick in the die 11, the flapper or flexible member 30 will flex downwardly toward the chute 27 and due to the fact that there is no end moving downwardly and rearwardly from the dies 11 and 15, the switch member 33 will 15 project through the slot 39 and contact with the contact member 40 and thus close the electric circuit to the solenoid 32 and effect movement of the operating lever 31 to a stopping position.

In the normal operation of the punch or press, the head 10 with the die 11 is moved in the direction of the lower substantially stationary die 15 and the supply sheet 21 is shifted by well known means relative to the dies 11 and 15. The die 11 is adapted to cut off an end 21a and this end 20 is formed of a suitable configuration depending upon the configuration of the confronting faces of the two dies 11 and 15.

At the present time considerable difficulty is experienced by reason of the fact that the ends 35 21a accumulate in the upper die 11 and these accumulated ends cause considerable damage to result both to the die 11 and to the entire press or punch apparatus. After the machine has been in operation the reciprocation of the head 10 is 40 sufficient to cause the flexible member 30 to be flexed downwardly and strike the bottom wall 28 of the chute 27 for the purpose of causing the cut ends to lie flat on the chute 27 and slide downwardly into a receptacle or conveyor at the lower end of the chute.

In the event one or more of the ends should stick in the die 11 or otherwise not be discharged onto the chute 27, the flexible member 30 will nevertheless be flexed downwardly toward the chute 27. In the absence of an end which may be engaged by the flexible member 30, the switch member 33 will engage within the slot 39 and contact with the stationary contact 40 so as to thereby close the electric circuit to the solenoid 32. Closing of the circuit to the solenoid 32 will effect 55 movement of the operating lever 31 to a stopping position.

With an attachment of this kind the press or punch will be automatically stopped when not more than two ends have accumulated in the die member 11 and these ends may then be removed from the die 11 and machine operated in the usual manner. The accumulation of two ends in the die 11 will not be sufficient to cause any material damage to result to the dies 11 and 15 or to the machine proper so that an attachment of this kind will provide an effective means for preventing damage to the machine in the event the ends are not discharged into the chute 27 in the normal manner. This switch device may be mounted on the present parts of a positioning machine or press, it only being necessary to form an opening 39 in the chute 27 so that the contact member 40 may be attached to the underside of the chute 27 within the opening 39. The switch member 33

may be secured to the flapper or end engaging member 30 and connected to the present lever operating solenoid which now forms a part of a machine. A device of this kind has been placed in actual operation and has been found to be more efficient than devices heretofore available particularly in view of the fact that this device is not affected by vibrations of the machine so that the device will not get out of order by such vibrations. In addition the safety attachment is of an exceedingly simple character embodying a small number of parts so that the safety device will not materially increase the cost of the punching machine or press.

It will be understood that when the starter lever 31 is initially shifted to start up the machine or press, the solenoid 32 is disconnected from the electric supply source by means of a cut-off switch 42 which is connected to one side of the supply source. When the press begins to run and the punched material moves through the machine the solenoid is connected to the electric supply source by means of the manually operated switch 42 so that if the material does not move regularly from the dies, the circuit closer 33 will contact the stationary switch member 40 and energize the solenoid 32 and effect movement of the operating lever 31 to a machine stopping position.

What I claim is:

1. A safety attachment for a punching machine having a movable die, a stationary die and a discharge chute for the formed article, said attachment comprising a flexible member adapted to be operatively connected at one end with said movable die, a switch member carried by said flexible member, and a contact below the upper surface of the chute in a position for engagement with said switch member when the chute is free of a formed article.

2. In combination a punching machine comprising a movable die, a stationary die, a discharge chute extending downwardly and rearwardly from said stationary die for guiding a formed article, a starting and stopping lever for causing actuation of said movable die, a solenoid connected to said lever and adapted upon energization thereof to shift said lever to a stopping position, a switch member movable with said movable die and connected to one side of said solenoid and a contact fixed relative to said chute in a position for engagement with switch member

to thereby close a circuit to said solenoid when the chute is free of a formed article.

3. In combination a punching machine comprising a stationary die, a movable die, a discharge chute inclined downwardly from said stationary die for guiding the punched material away from said dies, said chute having an opening therein, a flexible member fixed at one end relative to said movable die and adapted upon downward movement of said movable die to flex toward said opening in said chute, a rockable operating lever for causing actuation of said movable die, a solenoid connected to said lever for shifting said lever to a stopping position, a contact disposed in said opening of said chute and positioned below the upper face of the chute bottom, a switch member carried by said flexible member in a position to engage said contact when an article punched out by said dies sticks within one of said dies, said switch member being connected to said solenoid to thereby close a circuit to the latter for shifting the lever to a stopping position upon the sticking of the article.

4. In a punching machine having a stationary die, a movable die, a starting and stopping lever, a lever shifting solenoid for shifting said lever to a stopping position, a discharge chute for the formed article and a flexible article striking member, carried by said movable die for flatwise positioning the article in the chute; a safety attachment for energizing said solenoid upon failure of the article to slide downwardly of said chute, including a circuit making and breaking means connected to said solenoid and carried partly by said flexible member and partly arranged below said chute.

5. In a punching machine having a starting and stopping lever, a solenoid connected to said lever for shifting said lever to a stopping position, a pair of material punching dies and a discharge chute leading from said dies; a safety attachment for energizing said solenoid when an article fails to move over said chute, said attachment including a stationary switch part fixed relative to said chute, a movable switch part correlated with said stationary part, said movable part being connected with said solenoid, and means swingably mounting said movable part for movement with one of said dies.
